UNITED STATES PATENT OFFICE.

THOMAS F. PAYNE, OF PITTSBURG, PENNSYLVANIA.

WATER-CLOSET AND FLUSHING-VALVE THEREFOR.

No. 845,373.

Specification of Letters Patent.

Patented Feb. 26, 1907.

Application filed January 23, 1905. Serial No. 242,206.

To all whom it may concern:

Be it known that I, THOMAS F. PAYNE, a citizen of the United States, residing at Pittsburgh, in the county of Allegheny and State of Pennsylvania, have invented new and useful Improvements in Water-Closets and Flushing-Valves Therefor, of which the following is a specification.

My invention has relation to water-closet and flushing-valve in which the ordinary pressure of the street-main is used for flushing, and thus obviating the use of a separate tank for each closet. In water-closets and valves of this class heretofore in use the valve is usually closed by the pressure of a minimum quantity of water which is permitted to escape from the service-pipe through a minute orifice to the top of the plunger into a chamber in which the plunger slides and upon the top of the valve, and thereby as the amount of water in the upper chamber increases the pressure upon the top of the plunger closes the valve. There are many serious objections to this form of a valve, the principal one being that the orifice through which the water is carried from the inlet to the top of the valve is necessarily of minute diameter and will of course in time become clogged and closed up. This objectionable feature is greatly increased where the water contains any impurities—such as mud, sand, lime, acids, &c.—as any of these ingredients are apt to clog up the minute orifice, and thus prevent its operation, also in many cases binding and grinding the piston or plunger and the walls of the cylinder in which the piston slides, causing leakage and interfering with the operation of the valve. Another defect in this form of valve is the attachment of the handle to the body of the valve, this attachment being imperfect and causing leakage. Another objection in siphon-acting closets heretofore in use is the large water-supply required to flush the closet.

My invention consists, in a water-closet and valve, of devices by means of which the flushing-stream is controlled and directed alternately to different parts of the closet, devices for controlling the closing movement of the valve, devices for keeping the drag-leg of the closet full of water during the operation of the closet, and in the arrangement and combination of the parts by which a comparatively small water-supply and pipe therefor may be employed.

My invention further consists in the construction, combination, and arrangement of parts more fully described hereinafter and specifically pointed out in the claims.

In the accompanying drawings, illustrating my invention, Figure 1 is a vertical sectional view of a valve illustrating a part of my invention. Fig. 2 is a vertical sectional view at right angles to Fig. 1. Fig. 3 is a vertical sectional view of the closet. Fig. 4 is a top view of the same.

The casing of the valve consists of three separate castings 1 2 3, the portion 1 being the main body of the casing, the central portion 2, which is attached to the upper end of 60 1 by means of a threaded socket, contains the controlling device, which controls the closing of the valve and is separated from the lower portion 1 by means of the frictionless packing or folding diaphragm 21, which, as 70 shown in the drawings, has its upper end bent over and serves as a washer between the inner connecting-partition 5 and 6. The casting 3 is attached to the upper portion of the part 2 by a screw-socket, a suitable packing between the two preventing the escape of the liquid contained in the interior of the chamber 2'. The casting 3 is provided with ordinary coupling devices for the attachment 80 of an inlet-pipe from the water-supply, and an opening closed by a plate 8 permits the insertion of a lever 10, having a handle 11, attached to a shaft 12, by means of which the valve is raised. At the bottom of the 90 casing 1 is a coupling 13, which is attached to the inflow of the closet and through which the water after passing through the valve passes into the closet. The valve 14, seating in a partition 15, has attached to its bottom a cup 16, closed at both its ends and having an inlet-port 17 in its upper portion and an outlet-port 18 in its lower portion.

When the valve is raised by means of the lever 10, the water passes from the inlet 7 into the opening 17, which is then above the valve-seat 15, and passing through the body of the cup into the channel 19, through the port 18, and from thence into the channel 20, which leads to the flushing-rim of the closet.

A folding diaphragm 21, having its lower edge attached to the upper portion of the valve 14 and its upper edge attached to casting 2, prevents the passage of water into chamber 2'. A rod 21^x, attached to the up-

per side of the valve 14, passes through the center of this folding diaphragm and is attached to a valve 22, situated in the chamber of the casing 2. This valve 22 seats itself upon an opening in a plunger 23 and has on its lower portion lugs 24, which when the valve is raised a short distance come in contact with and raise the plunger 23 to the top of the chamber 2' in the casing 2. A rod or screw 25, which is attached to the top of the valve 22 and has an orifice 26 through the center of its lower portion and openings 27 in its side, is also attached to the top of the valve 22. The chamber 2' is adapted to contain and should be filled with a liquid, which liquid may be glycerin, water, oil, or any other suitable liquid.

When the valve 14 is raised from its seat and the plunger 23 is raised to the top of the casing, the liquid contained in the chamber 2' is forced by the raising of the plunger from the upper portion of the chamber through the opening of the valve 22 into the lower portion of the chamber and maintains the valve 14 and its connections in an elevated position, permitting the water to flow, while the valve remains raised, from the inlet 7 through the port 17, cup 16, port 18, and channels 19 and 20 into the rim 32 of the closet. When the handle 11 is released, the weight of the handle, together with the weight of the valve 14 and its cognate parts and the frictional pressure of the water passing through the valve 14, causes the square rod 21^x to drop sufficiently to close the valve 22 on its seat in the piston 23. This prevents the return of the liquid from the lower portion of the chamber 2' to the upper portion through the comparatively large opening of the valve 22. This same pressure of the piston 23 under the weight of the valve 14 and cognate parts, together with the frictional pressure of the water passing through the valve 14, also causes the liquid in the chamber 2' to flow slowly through the small passages 27 and 26, and thus pass from the lower to the upper portion of the chamber 2', permitting the piston to gradually descend in the chamber 2' as the liquid is displaced and permitting the valve 14 to close on its seat.

During the period the handle 11 is raised and also during the period occupied by the first part of the descent of the handle 11, the rod 21^x, and the valve 14 the water from the supply 7 passes, as already described, into the rim 32 of the closet and continues to pass thereto until the port 18 in the cup 16 is carried from the channel 19 to the channel 19^x. As soon as this takes place and the port 18 is brought into conjunction with the channel 19^x the water from the inlet 7 ceases to pass through the channels 19 and 20 to the rim 32 of the closet and commences to pass through the channels 19^x and 28 of the valve to the

channel 29 and jet 29^x of the bowl of the closet and also, if desired, to a short auxiliary rim-channel 33. This flow of water through the channels 19^x and 28 continues until the valve 14 is closed.

When the cup 16 descends to the position where its ports 17 and 18 are respectively in front of the channels 19 and 19^x and before the valve 14 is seated, the water passes through both of the channels 19 and 19^x, and its force and volume being thus divided the closet ceases to siphon and the water acts as a refill until the water ceases to flow. As the port 17 is somewhat greater in depth than the depth of the valve-seat 15, the flow of water from the chamber 4 through the port 17 to the channel 19 will take place during the closing of the valve.

The closet, as illustrated in Fig. 3, has a hollow rim or chamber 32 extending around the circumference of the closet, in which chamber is a partition 30, and where it is desired there may be a second partition 31. The chamber 32, as already described, communicates with the channel 20, and it is provided with perforations 32^x, made at such an angle that the water flowing through them will produce a swirl in the closet. The purpose of the partition 30 is to cause the water to flow in but one direction through the chamber 32.

The means for carrying the water from the channel 20 and 28 to the body of the closet is composed of what I term a "twin pipe or connection," which is made in a single piece 34, having central partitions 35, thus obviating the use of two separate pipes and their connections, and thereby lessening the cost of the fittings and also the danger of leakage arising from an increased number of joints. I also provide a washer 36, having a partition coincident with the partitions in the pipe 34, so that a perfectly tight joint will be formed between the pipe 35 and the connection 36, suitable washers being interposed between them, the coupling 13 having an elongated flange through which bolts pass for its attachment to the closet.

The operation of the valve and the consequent delivery of the water first to the rim of the closet, then to the jet, and then to both the rim and the jet has been fully described in the description of the parts. The effect of the delivery of the water in the closet is as follows: The water which passes to the chamber 32 of the rim of the closet passes from the same at an angle under pressure, thus producing a swirl which piles the water in the bowl, retarding its flow therefrom and scouring the bowl. As soon as the water ceases to pass through the chamber 32 and while the water is piled up in the bowl the jet action through the jet 29^x commences. This jet, also being under pressure, strikes the solid body of water in the up-leg of the bowl and

spreading somewhat therein pushes this body of water contained in the up-leg over the dam 50 of the trap and into the drag-leg 51, forming a solid plug of water in the drag-leg 51 and cross-leg 52, thus producing a combined siphon and ejector action. This combined action of the water draws the contents of the bowl after it through the legs of the closet. While the combined siphon and ejector action is taking place, if the bowl is provided with the chamber 33 water will flow through the channel 29, through the chamber 33, and into the closet.

To prevent the water which flows through the casing 1 from escaping through the orifice by which the handle-lever enters the casing and to obviate the necessity of a packing-box which is liable to permit leakage and create friction, I employ a flexible diaphragm 39, which, as shown in Fig. 1 of the drawings, is placed in the lower chamber 40 and is held in position over the opening thereof by means of the plate 8 and the bolts 9. The lever 10 passes through this diaphragm and is closely clamped thereto by the screw 41 drawn into the bell-crank 42. The flange 43 pressing against the outside of the diaphragm 39 prevents the escape of any water from the chamber 40 to the outside and through the opening through which the handle-shaft enters, and this opening does not, therefore, require to be packed. This folding diaphragm consists of a single piece of flexible material, such as rubber, or I may, if I desire, make it of thin metal—such as steel, brass, &c.—which will bend sufficiently to permit of the easy operation of the lever 10. I have also embodied this same principle in the diaphragm 21, placed in the chamber 4 to prevent the passage of water into the liquid-chamber where the same is made in the shape of an accordion plait, although it might be made as a simple elastic or pliable cylinder.

The advantages of my invention result from the combination of a direct-pressure alternately-acting valve with a closet-bowl having rim-orifices adapted to produce a swirl and a jet directed toward the up-leg of the bowl; also, from the combination of this bowl with a valve having a retarding device acting entirely independently of the water in the main.

The advantages resulting from the construction hereinbefore described are that the closet is positive in action, that it has a joint and combined siphon and ejector action, which effectually cleans the bowl without any pounding or noticeable noise, that it acts with but a comparatively small amount of water, requiring but a small supply-pipe, and that the parts are not liable to leakage or to get out of order.

I do not desire to limit my invention to the order of the flow of water through the channels leading from the valve, as herein de-

scribed; nor do I desire to limit myself to the form and arrangement of parts shown in the drawings and described in the specification.

Although I have described the valve and bowl combined to produce a new and useful result, I do not desire to abandon my right to embody the useful and novel features of these parts independently of each other in separate applications for Letters Patent.

What I claim as new, and desire to secure by Letters Patent, is—

1. In a water-closet, a bowl having a rim-orifice adapted to produce a swirl in the bowl and a jet directed toward the up-leg of the bowl, in combination with a valve having a channel leading from the street-main to the rim-orifice, a channel leading from the street-main to the jet, and devices for directing the flow of water first through one of these channels and then through the other.

2. In a water-closet, a bowl having a rim-chamber provided with orifices arranged to cause a swirl of water in the bowl, having a jet-orifice directed upwardly in the up-leg of the bowl, and having an up-leg, a drag-leg, and a cross-leg, in combination with a valve having a channel leading from the street-main directly to the rim-chamber of the bowl, a channel leading from the street-main directly to the jet, and devices for causing the water to flow first through one of these channels and then through the other.

3. In a water-closet, a bowl having a rim-orifice adapted to produce a swirl and a jet directed upwardly in the up-leg of the bowl, in combination with an alternately-acting valve having a channel leading to the rim-orifices, a channel leading to the jet, a main chamber communicating with the street-main, a main valve having ports adapted, when the valve is opened, to direct the flow of water from the street-main first to one channel, and as the valve closes to close communication with this channel and to open communication with the other channel, and having a liquid-chamber adapted to contain liquid separated from the main chamber and containing a piston, an auxiliary valve arranged in the piston and having a port for the passage of the liquid when the valve is open, a smaller passage for the return-flow of the liquid when the valve is closed, and a rod connecting the auxiliary valve with the main valve, whereby the closing of the main valve is retarded by the liquid in the liquid-chamber.

4. In a water-closet, a bowl having a rim-orifice and a jet, in combination with a valve having a channel leading to the rim-orifice and a channel leading to the jet, and having a cup or barrel provided with a port which, when the valve is fully open, communicates with this chamber which is connected directly with the street-main and which also, when the valve is partially closed, communi-

cates both with the chamber and with one of the channel's leading to the bowl, and provided with a second port which, when the valve is open, communicates with one channel leading to the bowl and as the valve closes is shut off from this channel and is brought into communication with the other channel leading to the bowl.

5. In a water-closet, a bowl having a rim-chamber, a partition or wall in the chamber arranged to cause the water to flow from one end of the chamber to the other, orifices inclined in the chamber to produce a horizontal swirl, a jet, and channel's leading to the jet and to the rim-chamber, in combination with a valve for directing a stream of water first to one channel and then to the other, substantially as specified.

6. In a water-closet, a bowl having a rim-orifice, adapted to produce a swirl in the bowl, having a jet, and having channels leading to the rim-orifice and to the jet, in combination with a valve-casing having a main-valve chamber provided with a valve 20 adapted to direct the flow of water first to one channel and then to the other, and having a liquid-chamber provided with a piston

and with a flexible head, and a rod located in the flexible head and connecting the piston and main valve.

7. In a water-closet, a bowl having an orifice adapted to produce a swirl in the bowl and a jet directed toward the up-leg of the bowl, in combination with a valve having a channel leading to the swirl-orifice, a channel leading to the jet and devices for directing the flow of water first through one of these channels and then through the other.

8. In a water-closet, a bowl having an orifice, a jet, an up-leg, a drag-leg, and a cross-leg, in combination with a valve having a channel leading to the orifice, a channel leading to the jet, and devices for directing the flow of water first through one of these channels and then through the other, thus 40 producing a combined ejector and siphon action.

In testimony whereof I have signed my name to this specification in the presence of two subscribing witnesses.

THOMAS F. PAYNE.
